UNITED STATES PATENT OFFICE.

WILLIAM H. HASKELL, OF PHILADELPHIA, PENNSYLVANIA, ASSIGNOR TO HIMSELF, G. W. HASKELL, AND H. J. HASKELL, OF SAME PLACE.

IMPROVEMENT IN SPRINGS FOR VEHICLES.

Specification forming part of Letters Patent No. **154,247**, dated August 18, 1874; application filed July 6, 1874.

To all whom it may concern:

Be it known that I, WILLIAM H. HASKELL, of Philadelphia, Pennsylvania, have invented an Improvement in Spar-Wagons, of which the following is a specification:

The object of my invention is to impart greater freedom of movement to the body, spars, and springs of a spar-wagon than in those of ordinary construction, and I attain this object by suspending the body A of the wagon from the spars B B by double-jointed connections D, in the manner fully described hereafter, and as illustrated by the plan view, Figure 1, and transverse section, Fig. 2, of the accompanying drawings.

The front and rear axles F and F' of the wagon are connected together by a suitably-braced longitudinal bar, G, and to the upper sides of these axles are secured "half-springs" H, which support at their outer extremities the longitudinal spars or side bars B B, the latter being in turn connected to the body A of the wagon by the transverse rods J.

Spar-wagons of this character combine the advantages of lightness and strength with economy of construction, but a principal objection to their use, as heretofore constructed, has been the imperfect action of the springs and spars, and a consequent unyielding and jolting movement of the body. This rigidity of the parts was caused by securing the cross-pieces J of the body, directly and permanently to the spars, which prevented the latter

from spreading, and otherwise accommodating themselves to the movements of the springs, an objection which I have effectually overcome by interposing links D between the said cross-pieces J and the spars, thus permitting the latter to yield independently at one or both ends, and the body consequently to undulate as required without any of the usual unpleasant jolting.

The links D may be variously constructed, and may be jointed to the spars and body in any suitable manner. In the present instance they are jointed directly at one end to the extremities of the cross-pieces J which extend beneath the wagon-body, and at their opposite ends to clips a which embrace the spars.

Any lateral rocking movement of the body upon its double-jointed connections is prevented by setting the latter at an angle as shown in Fig. 2.

I claim as my invention—

The combination of the body A, springs H H, transverse bars J, and links D, connecting the bars to the under sides of the spars as set forth.

In testimony whereof, I have signed my name to this specification in the presence of two subscribing witnesses.

WM. H. HASKELL.
